UNITED STATES PATENT OFFICE.

ADOLPH A. THOMAS, OF NEW YORK, N. Y.

TELEPHONE INSTRUMENT.

Application filed October 28, 1925. Serial No. 65,282.

My invention is for a new and improved telephone instrument equally well adapted for use as transmitter and receiver. The object of my invention is to provide an instrument of high efficiency and yet exceedingly simple construction. As will appear later, the instrument of my invention is particularly useful for radio broadcasting and reception, although not limited to that field.

One of the main features of my invention comprises an edge-free diaphragm of conducting material resiliently mounted to vibrate in a magnetic field and adapted to be connected in a suitable circuit, either to generate variable currents by its mechanical vibrations or to be acted upon by variable currents to produce mechanical movements thereof. This vibratory acoustic unit comprises a central rigid section which constitutes the diaphragm, and a pair of resilient end sections which support the diaphragm for operative movement in the magnetic field. The diaphragm and supporting sections may be made of a single piece of resilient non-magnetic sheet metal. As an example of such a metal I may mention aluminum and aluminum alloys, which have the additional advantage of lightness. The supporting extensions of the diaphragm are preferably corrugated transversely to provide the required resiliency.

In a preferred embodiment of my invention, the vibratory acoustic unit is supported on and between a pair of spring arms which are adjustable to regulate the normal tension or resiliency of the vibratory unit. This adjustment may be made from outside the casing of the instrument.

Various other features and advantages of my new telephone instrument will become apparent from a detailed description of suitable embodiments shown in the accompanying drawings, in which—

Fig. 1 shows in vertical cross-section a loudspeaking telephone receiver constructed in accordance with my invention, the section being taken on line 1—1 of Fig. 2;

Fig. 2 is a plan view in section on line 2—2 of Fig. 1;

Fig. 3 is a fragmentary view in cross-section showing a modified form of connection for adjusting the normal resiliency of the vibratory unit from outside the casing;

Fig. 4 is a vertical cross-section on line 4—4 of Fig. 5, showing a telephone transmitter embodying my invention;

Fig. 5 is a face view of the construction shown in Fig. 4, with the front plate or cover removed;

Fig. 6 is a transverse cross-section on line 6—6 of Fig. 5;

Fig. 7 is a fragmentary detailed view to show a form of readily separable connection between the end covers and the body of the casing in Figs. 4, 5 and 6;

Fig. 8 is a fragmentary view, partly in section, showing the automatically adjustable connection between the spring frame which supports the vibratory unit and the manually operated rod for adjusting the spring arms; and

Fig. 9 is a diagrammatic view of a modification in which the edge-free diaphragm is resiliently supported by coil springs.

Referring first to Figs. 1 and 2, the various parts of the operative mechanism are enclosed within an outer casing indicated as a whole by C. This casing, which may be made of non-magnetic sheet metal or molded of suitable composition material, 80 consists of a cylindrical body section 1, a top or cover 2 and a laterally extended base 3. The cover 2 is preferably secured to the casing by a readily separable connection, such as screw-threads 4 or otherwise. A 85 hollow tubular extension 5 projects centrally from the cover 2 for receiving a horn 6 or other suitable amplifier. A horizontal annular flange 7 extends laterally from the lower end of the body section 1 and forms 90 with the base 3 a horizontal circular recess 8 in which is mounted a supporting disk 9 of suitable non-magnetic or insulating material. This disk fits snugly at its periphery against the right-angled shoulder formed by 95 the lateral flange 7 and the upper portion of the base section 3, and is held in place by suitable fastening devices 9', such as removable screws or bolts.

On the base-plate or disk 9 is mounted a 100 magnet M, which is preferably of the permanent type. As shown in the particular embodiment illustrated, this magnet is bent substantially U-shaped and consists of a base 10, a pair of upright sides 11 and a pair of 105 inwardly projecting pole pieces 12, one of which is marked the north pole (N) and the other the south pole (S). One or more bolts 13, or other suitable fastening means, hold the magnet M securely in place on the base 9. 110

As seen in Fig. 2, the pole-pieces 12 of the magnet are separated by an air gap 14, and

in this air gap is operatively mounted a diaphragm 15. In the present instance, the diaphragm 15 is provided at opposite ends with a pair of integral extensions 16, which 5 are transversely corrugated as indicated at 17. The diaphragm is a rigid plate or disk of sufficient area to operate efficiently for transmitting and receiving sound waves. When I refer to the diaphragm as a plate or 10 disk, I do not limit myself to any specific configuration, but I use the terms in the broadest possible sense. The parts 15 and 16 constitute an acoustic vibratory unit, which may conveniently be stamped or cut from a 15 single piece of non-magnetic sheet metal having sufficient resiliency. The metal aluminum and some of its alloys will answer this purpose very well, but I want it understood that any suitable metal may be used for the 20 vibratory unit.

The outer ends of the corrugated extensions 16 are attached to a pair of spring arms 18, which extend upwardly from a cross-piece 19. The members 18 and 19 are 25 preferably shaped from a single strip of resilient material and thus constitute a single supporting frame for the vibratory unit. Screws 20, or other fastening devices, secure the supporting frame rigidly in position 30 on the disk 9. Since the supporting member 18-19 is arranged at right angles to the magnet, the latter does not interfere with the mounting of the frame within a casing having a diameter only slightly greater than 35 the length of the magnet. As the vibratory unit 15-16 is connected in circuit, the extensions 16 should be insulated from the metallic supporting arms 18. This may be accomplished in any suitable way. In Fig. 1, 40 I have shown the ends of the extensions 16 rigidly clamped to the arms 18 by insulated bolts 21, by which I mean bolts encased in or surrounded by a sleeve of insulated material. An insulated washer 22 is interposed 45 between the extensions 16 and the inwardly extending flanges 18' of the spring arms 18. If desired, clamping plates 23 may be inserted 50 between the bolts 21 and the extensions 16 to insure a rigid connection for the vibratory unit. The plates 23 may be of metal or hard insulating material.

In order to adjust the supporting arms 18 toward and from each other for the purpose 55 of varying the normal tension or resiliency of the extensions 16, I provide a two-part rod 24 having screw-threaded ends 25 arranged to engage in a screw-threaded cylindrical finger piece 26. The screw-threads 25 run in opposite directions, so that when the 60 finger piece 26 is turned in one direction, the rod sections 24 are separated, and when the finger piece is turned the other way, the rod sections are drawn together. The outer ends of the rod 24 are provided with cylindrical or transversely elongated hubs 27. These

hubs or bearing pieces are held in correspondingly shaped recesses formed by lateral bends 28 in the supporting arms 18. Retaining plates 29 are secured to the arms 18 by screws 20, or otherwise, for holding the bearing hubs 27 in firm contact with the arms 18 during the axial movements of the rod 24. It is clear from Fig. 1 that, when the two sections of the rod 24 are forced apart by 70 turning the knurled finger piece 26, the resilient arms 18 are likewise spread apart and the normal resiliency or tension of the vibratory unit 15-16 is increased. Conversely, when the finger piece 26 is turned the other way to draw the rod sections 24 closer together, the spring arms 18 move toward each other and the tension of the vibratory unit is decreased. The function of the cylindrical or elongated bearings 27 at the 75 ends of the rod 24 is to compensate for the rocking movements of the arms 18 while the rod 24 moves in a straight line. The retaining plates 29 are provided with openings 29' which are slightly larger than the diameter of rod 24, so as to allow rocking movement 80 of the arms 18 without binding the rod 24. The bearing pieces 27 are preferably elongated transversely of the arms 18, in order to prevent rotation of the rod 24 when the same is adjusted by the rotary finger piece 95 26. If the bearing hubs 27 are made spherical, as they might be, it will be necessary to clamp them so firmly in place by means of the retaining plates 29 that rotation of the rod 24 will not take place during the axial 100 adjustment thereof.

For conveniently connecting the vibratory unit 15-16 in circuit, the ends of the extensions 16 may be prolonged beyond the spring arms 18, as indicated at 16', and to these projecting ends are secured conductors 30 and 31, which are led through a hole 32 in the base 9 to a pair of binding posts or terminals 33 and 34 secured to the underside of disk 9 within the base section 3 of the outer casing. The terminals 33 and 34 are adapted to receive 105 a pair of circuit leads 35, which pass through an insulated hole 36 in the base 3. The foregoing arrangement provides a simple way for connecting the vibratory unit 110 15-16 in circuit. The leads 30 and 31 are readily connected to the projecting ends 16' of the extensions 16 by soldering, or in any other practical way, and this is done before the base disk 9 and the parts carried thereby are inserted within the outer casing.

The operation of the instrument above described as a telephone receiver will be understood without further explanation. I need only say that, as variable currents pass through the telephone circuit in which the vibratory conducting unit 15-16 is connected, the diaphragm 15 will vibrate transversely in the air gap 14 between the magnetic pole pieces, and these vibrations will corre- 115 120 125 130

spond to current variations in the circuit. Consequently, the vibrations of diaphragm 15 will reproduce the sound waves which originally caused the current variations in the telephone receiving circuit. Since the diaphragm is opposite and close to the sound opening 5 in the cover 2, the vibrations of the diaphragm will set in motion the column of air in the sound amplifier 6, so that the acoustic reproduction will be amplified sufficiently to be heard at a distance. As the diaphragm 15 is free or unbound at the edge, it has no fundamental note of its own and responds instantly and with equal fidelity to all vibrations occurring within the range of ordinary speech or music. Also, the vibratory unit 15-16 can be made exceedingly light and its inertia is thus reduced to a minimum. Indeed, it is possible to make this vibratory acoustic unit so small and so light that for practical purposes its inertia becomes negligible. This obviously adds to the sensitiveness and efficiency of the instrument. Owing to the way in which the diaphragm 15 is supported by the resilient extensions 16, it is free or floating at the edge and therefore vibrates with substantially equal amplitude over its entire area. I have attempted to indicate this in a crude way by the dotted lines 15' in Fig. 1. In the practical operation of the instrument, the amplitude of vibration of the diaphragm 15, even at its maximum, will be but a very small fraction of an inch, and so the pole pieces 12 need not be very thick.

The volume of the reproduction, and to some extent also its quality, is controlled by regulating the normal tension of the vibratory unit, as previously described. For instance, by spreading the arms 18 and thus increasing the tension of the extensions 16, the normal load (if I may call it that) on the diaphragm 15 is correspondingly increased, and the diaphragm will not vibrate as freely or with the same amplitude (ceteris paribus) as when the tension on the member 16 is relaxed by bringing the arms 18 closer together. The finger piece 26, therefore, regulates the degree of loudness of the reproduction. It goes without saying that the resiliency of the extensions 16 should be such that the diaphragm 15 instantly responds without lag or sluggishness to variations in current passing therethrough.

The particular shape or outline of the diaphragm is not material, provided it has sufficient area for proper reproduction and is otherwise of such suitable shape that the flux across the air gap produces the required magnetic field for the diaphragm. In Fig. 2, the pole pieces 12 are shaped to produce an air gap which is slightly narrower at the ends than at the middle, in order to provide a more uniform distribution of the flux across the air gap by reducing the reluctance

across the ends thereof. The diaphragm 15 is shaped at its opposite sides in conformity with the shape of the polar faces that define the air gap. Since the diaphragm 15 is non-magnetic, there is no normal drag on the diaphragm in one direction or the other by the magnetic field.

Attention is called to the fact that, since all parts of the operative mechanism are mounted on the base 9, they can be secured upon the base and properly adjusted before insertion into the casing. This makes the assembling and final adjustment of the instrument comparatively easy, because the subsequent handling of the base and the parts carried thereby does not disturb any previous adjustment. By simply unscrewing the cap or cover 2, all parts are fully exposed for access.

If desired, the cylindrical body 1 of the outer casing may be provided with sound outlets 37 for the lateral emission of sound waves produced by the diaphragm in the volume of air lying beneath it in the casing. In this way, the diaphragm sends out a double series of sound waves—one train of waves passes upwardly through the amplifier 6, and another train of waves is sent horizontally through the openings 37 in all directions. This not only gives a stronger reproduction, but also results in a more even distribution of sound throughout the room in which the loudspeaker is located.

In the modification shown in Fig. 3, the rod sections 24 for adjusting the spring arms 18 are actuated from outside the casing by means of a knurled knob or thumb piece 38. The screw-threaded ends of the rod sections 24 engage a cylindrical screw-threaded piece 39 provided on its periphery with gear-teeth 40. In other words, the connecting piece 39 is in effect a small toothed wheel or pinion 40. The knob 38 is connected to the outer end of a rod 41. To the inner end of rod 41 is secured a small gear-wheel or pinion 42 arranged to mesh with pinion 40. The rod 41 is supported at one end in the hub 43 of the casing, and at the other end by a suitable bracket 44 mounted on base 9 or otherwise held in position. By turning the knob 38, the pinion 40 is rotated one way or the other to separate the rod sections 24 or draw them closer together. The rod sections 24 in Fig. 3, as well as those in Fig. 1, may be regarded as a single rod axially adjustable in length. The screw-threaded engagement between the rod sections 24 and the member 26 or 39 is such that very delicate adjustments of the spring arms 18 are effected by turning member 26 or knob 38.

In Figs. 4, 5 and 6 I have shown a telephone transmitter embodying my invention and particularly adapted in radio broadcasting. The instrument is mounted on a suitable base 45 to which is secured a casing 46,

as by screws 46'. The casing 46 is shown cylindrical in form, but it may have any other convenient shape. The rear end of casing 46 is closed by a base plate or disk 47, which is removably secured in place by suitable fastening devices, such as screws 47'. The disk 47 carries the electro-magnetic operating mechanism. A permanent steel magnet M' is secured to the disk 47 by fastening devices 48. In order to secure as great a length of magnet as possible, I prefer to shape it as shown in Fig. 4, with the pole pieces 49 extending toward each other to provide an air gap 50 arranged centrally of the casing. In the magnetic air gap 50 operates a diaphragm 51, which in this instance is approximately square-shaped in order to extend closely from one polar face to the other. The diaphragm 51 is provided with a pair of resilient extensions 52 supported at their outer ends by resilient arms 53. The extensions 52 are preferably corrugated transversely so as to provide the proper degree of resiliency for the diaphragm 51, which should respond instantly and properly to the sound waves projected against it. The diaphragm 51 and its resilient supporting extensions 52 constitute a vibratory unit substantially identical with the vibratory unit 15-16 previously described in detail. Similarly, the connections between the extensions 52 and the spring arms 53 are like the connections between the extensions 16 and the spring arms 18 of Fig. 1. Consequently, in order to avoid needless repetition, it will be understood that the previous detailed description of the construction and operation of the vibratory unit 15-16 and the supporting spring arms 18, shall be considered as fully applicable to the vibratory unit 51-52 and the supporting arms 53.

In the construction of Figs. 4, 5 and 6, the resilient supporting arms 53 are adjusted by means of a single rod 54 having opposite screw-threads 55 and 56 near its ends. The rod 54 projects at its ends through elongated openings 57 in the arms 53. On the screw-threads 55 and 56 of rod 54 are mounted cylindrical bearings 58, which are screw-threaded to engage the corresponding screw-threads of the rod. The cylindrical bearings 58 are held tightly in cylindrical recesses formed by offset portions 59 of the arms 53 and by retaining plates 60 rigidly attached to these arms. The retaining plates 60 are each provided with a hole 61 which is slightly larger than the projecting end of rod 54. When the rod 54 is rotated in one direction, the spring arms 53 are drawn together, and when it is turned in the reverse direction, the spring arms are forced apart, precisely as described in connection with the two-part rod 24 in Fig. 1. The purpose and function of the cylindrical bearings 58 are exactly the same as ex-

plained in reference to the bearings 27 of Fig. 1. The elongated openings 57 and 61 in the spring arms 53 and retaining plates 60, respectively, allow for rocking movement of the arms 53 without interfering with the rotation of rod 54.

In order to allow ready and easy manipulation of the adjusting rod 54, I connect the same to a suitable finger piece, such as a rotary knob 62, projecting from the side of casing 46. In the present instance, the knob 62 is provided with a screw-threaded extension 63 having a slot 64 adapted to receive snugly a flat projection 65 at one end of rod 54. The knob 62 is held against axial movement by a washer or like member 66 screwed in proper position on the extension 63. This separable connection between the finger piece 62 and the rod 54 makes it possible to insert the entire mechanism carried by the base 47 into the casing 46 as a unit. By turning the knob 62 in such a direction that the slot 64 faces directly toward the rear of casing 46, the flat projection 65 of rod 54 will automatically enter this slot when the mechanism is inserted into the casing from the rear. It will be noticed that the entire length of rod 54 is less than the diameter of casing 46, so that the rod does not interfere with the insertion and removal of the entire mechanism into and from the casing.

On the rear face of base plate 47 are mounted suitable terminals or binding posts 67, to which are connected conductors 68 leading from the extensions 52 of the vibratory unit. Circuit leads 69 are connected to the terminals 67 and these leads may conveniently be led out of a hole 70 in the lower end of the rear cover 71. This cover is preferably mounted on the casing so as to be readily removable therefrom. For instance, the casing 46 may have a series of headed pins or lugs 72 arranged to engage bayonet slots 73 in the cover, as shown in the fragmentary view of Fig. 7. The front cover 74 of the instrument is provided with a sound opening 75 opposite the diaphragm 51. If desired, the opening 75 may be covered with gauze or similar material. The cover 74 is preferably mounted on the casing so as to be quickly and easily removable to expose the inside mechanism. For this purpose, a separable bayonet slot connection may be used, as shown in Fig. 7, or any other practical connection. The covers 71 and 74 may be of identical shape and formed from sheet metal, fiber, composition material, etc., in the same die or mold, and they may be made as ornamental as desired.

It is self-evident that the various parts of the instrument, other than the magnet itself, should be made of non-magnetic material, so as to prevent the weakening of the magnetic field across the air gap. There would,

perhaps, be no objection to making the spring arms 53 of magnetic material, because these arms are arranged at right angles to the magnet and outside the direction of the magnetic flux. The mere fact that the cross-connection of the arms 53 is in contact with the base of the magnet at the center or neutral part thereof, would not cause magnetic leakage through the arms 53, if the instrument is otherwise properly constructed. The same holds true for the spring arms 18 in Fig. 1.

The casing 46 may be provided with a series of small sound openings 76 to prevent the formation of air cushions back of the diaphragm 51 during the vibrations thereof.

Although I have described the instrument of Figs. 4, 5 and 6 as a transmitter, it is obvious that the same may be used as a receiver. In that event, it would perhaps be advisable to attach around the opening 75 a sound amplifying extension.

In Fig. 9, I have shown, in a diagrammatic way, a modification including a diaphragm 77 resiliently suspended by coil springs 78 arranged to operate in the air gap formed between the magnetic pole pieces 79 and 80 of a suitable magnet (not shown). Each pair of springs 78 is connected to a bar 81 affixed to a square rod 82, which is slidably mounted in a suitable support 83. The outer end of each rod 82 is screw-threaded at 84, and on this screw-threaded end is mounted a knob or other finger piece 85 for manual adjustment. By turning the knobs 85 one way or the other, the tension of the springs 78 is regulated, for the purpose previously described in reference to the diaphragm in Figs. 1 and 4. The springs 78 are preferably used as conductors for connecting the non-magnetic diaphragm 77 in the desired circuit. Otherwise, what has been said about the diaphragms 15 and 51 is applicable to diaphragm 77.

It will be clear from the foregoing description of the several embodiments illustrated in the drawings that I have provided a telephone instrument of simple construction and high efficiency in the electric transmission and reproduction of sound waves. The vibratory acoustic element is self-actuating, in that it requires no separate member to set it in operation. This acoustic element represents a construction of utmost simplicity.

The efficiency of the instrument is enhanced by the absence of a pivoted armature which is liable to strike the pole pieces, by the absence of an edge-bound diaphragm with a fundamental note of its own and connected to the armature by rods or links in which lost motion is almost unavoidable, and by the absence of any coil that is bound

to have a disturbing effect by its self-induction. The parts composing the operative mechanism in my new instrument are so few and may be so compactly arranged that the instrument can be constructed considerably smaller than shown in the drawings. I have purposely exaggerated the proportion of parts in the drawings for the sake of clearness, so that these drawings are not to be taken as actual working drawings.

Although I have herein shown and described certain specific constructions, I want it clearly understood that I have done so merely to explain my invention to those skilled in the art by selecting what I consider fairly representative examples of mechanical embodiments of my invention. It is obvious that the underlying ideas of my invention may be embodied in various other ways without sacrificing any of the advantages thereof.

What I claim as my invention is:

1. In a telephone instrument, a magnet having an air gap, an acoustic diaphragm of rigid non-magnetic conducting material resiliently mounted to vibrate bodily in said air gap, and means for connecting said diaphragm in an electric circuit.

2. In a telephone instrument, a magnet having an air gap, an acoustic diaphragm of rigid non-magnetic conducting material mounted to vibrate in said air gap in a direction at right angles to its own plane, and means connected to said diaphragm for resiliently supporting the same in said air gap, said diaphragm being adapted to form part of an electric circuit.

3. In a telephone instrument, a magnet having an air gap, an acoustic diaphragm of rigid non-magnetic conducting material mounted to vibrate in said air gap in a direction at right angles to its own plane, and connections at opposite ends of said diaphragms for resiliently supporting the same in said air gap, said connections being of conducting material to connect the diaphragm in circuit.

4. In a telephone instrument, a magnet having an air gap, an acoustic diaphragm of non-magnetic conducting material mounted to vibrate in said air gap in a direction at right angles to its own plane, connections at opposite ends of said diaphragm for resiliently supporting the same in said air gap, said connections being of conducting material to connect the diaphragm in circuit, and means for simultaneously adjusting the degree of resiliency of said connections.

5. In a telephone instrument having a magnetic air gap, an acoustic diaphragm of a non-magnetic conducting plate or disk mounted to vibrate as a rigid body in said air gap and adapted to be connected in cir-

- cuit, resilient extensions integral with said diaphragm for operatively supporting the same in said air gap, and means for adjusting the degree of resiliency of said extensions.
6. In a telephone instrument having a magnetic air gap, a rigid acoustic diaphragm of non-magnetic conducting material provided with resilient extensions for supporting the diaphragm for vibratory movement in said air gap, said diaphragm being adapted to be connected in an electric circuit and having a width greater than that of said extensions, so that the acoustic area of said diaphragm is sufficient for loud reproduction or to receive sound waves for transmission.
7. In an electric instrument having a magnetic air gap, a vibratory unit consisting of narrow resilient end sections and a central disk or plate of greater width and rigidity than said end sections, said end sections resiliently supporting said disk for vibratory movement in said air gap in a direction at right angles to the plane of said disk.
8. In a telephone instrument, a casing provided with a base, a frame secured to said base and having a pair of spring arms, and a diaphragm connected to and supported between said arms for vibratory movement, said frame and said diaphragm being attachable to and removable from said base as a unit.
9. In a telephone instrument having a magnetic air gap, a pair of supporting spring arms, resilient tension members connected to said arms, an acoustic diaphragm connected at opposite points to said members and arranged to vibrate in said air gap, whereby said diaphragm is resiliently supported by and between said members for bodily vibratory movement, and means for simultaneously adjusting said spring arms to vary the normal tension of said resilient members.
10. In a telephone instrument, an acoustic diaphragm in the form of a rigid plate or disk of sheet metal provided with resilient tension members connected to and projecting from opposite ends of the diaphragm.
11. A telephone instrument having means to provide a magnetic field, a plurality of resilient tension members, and a rigid edge-free diaphragm of non-magnetic conducting material supported by and between said tension members for vibratory movement in said field.
12. In a telephone instrument, a pair of adjustable arms, a vibratory unit arranged between said arms and connected thereto for support, said unit being inherently resilient, and means for simultaneously adjusting said arms to vary the normal resiliency of said unit.
13. In a telephone instrument, an edge-free vibratory diaphragm consisting of a rigid plate or disk resiliently supported and electrically self-actuating.
14. In a telephone instrument, a vibratory diaphragm provided with a pair of integral extensions projecting from opposite edges of the diaphragm for supporting the same, said diaphragm being of greater rigidity than said extensions.
15. In a telephone instrument, a one-piece vibratory unit of metal consisting of a rigid diaphragm and a pair of flat strips extending integrally from said diaphragm at diametrically opposite points thereof, said strips being transversely corrugated to provide a resilient support for the diaphragm.
16. In a telephone instrument, an acoustic diaphragm consisting of a rigid plate or disk, and means engaging the edge of said diaphragm at only two points diametrically opposite for resiliently supporting the diaphragm to permit vibration thereof with practically uniform amplitude over its entire surface.
17. In a telephone instrument, a substantially closed outer casing, a resilient vibratory unit in said casing, means for maintaining said unit constantly under tension, and means operable from outside said casing for controlling the normal tension of said unit.
18. In a telephone instrument, a substantially closed outer casing, a magnet in said casing, an acoustic edge-free diaphragm of sheet metal in operative relation to said magnet, a plurality of resilient tension members connected to opposite ends of said diaphragm for resiliently supporting the same for bodily vibratory movement, and means operable from outside said casing for adjusting the degree of resiliency of said members.
19. In a telephone instrument, a frame having a pair of spring arms, and a vibratory unit supported by and between said arms, said unit including a rigid edge-free diaphragm.
20. In a telephone instrument, a frame having a pair of spring arms, a resilient vibratory unit supported by and between said arms, and manually adjustable means for simultaneously moving said arms to vary the distance between the supporting ends of said arms and thereby controlling the resiliency of said vibratory unit.
21. In a telephone instrument, a frame having a pair of spring arms, a resilient vibratory unit supported by and between said arms, a manually adjustable rod engaging said arms to force them apart or bring them toward each other, and means included in the connections between said arms and said rod for automatically compensating for the rocking movements of said arms.
22. In an electric instrument, a base, a

substantially U-shaped magnet mounted on said base, a substantially U-shaped frame mounted on said base at approximately right angles to said magnet, and a vibratory unit supported by said frame in operative relation to said magnet.

23. In a telephone instrument, a frame having a pair of spring arms, a vibratory unit supported by and between said arms, a rotary finger piece, and connecting means between said finger piece and said arms for

simultaneously moving said arms toward or away from each other.

24. In a telephone instrument, a substantially closed outer casing, a resilient vibratory unit in said casing, means for maintaining said unit constantly under tension, a rotary finger piece outside said casing, and connections between said finger piece and said tensioning means to control the degree of resiliency of said unit.

ADOLPH A. THOMAS.
